Primary Examiner — Cynthia Underwood

(57) **CLAIM**

The ornamental design for a j-clip, as shown and described.

DESCRIPTION

FIG. 1 shows a perspective view of my design for a j-clip; FIG. 2 is a front view thereof; FIG. 3 is a back view thereof; FIG. 4 is a top view thereof; FIG. 5 is a bottom view thereof; FIG. 6 is a side view thereof; and, FIG. 7 is another side view thereof.

The j-clip of the present invention is designed to attach to a piece of webbing and can be used to clip things to.
